CLAIM

The ornamental design for a screw for replacing the
male component of a snap fastener, as shown and de-
scribed.

DESCRIPTION

FIG. 1 is a perspective view of a screw for replacing the
male component of a snap fastener embodying our new
design;

FIG. 2 is a side elevational view thereof, the front, back,
left and right side views being identical;

FIG. 3 is a top plan view thereof;

FIG. 4 is a bottom plan view thereof; and,

FIG. 5 is a transverse sectional view thereof.
